UNITED STATES PATENT OFFICE

2,598,398

HYDRAULIC CENTERING REEL

Frederick M. Littell and Rudolph A. Skriba, Chicago, Ill., assignors to F. J. Littell Machine Company, Chicago, Ill., a corporation of Illinois

Original application March 26, 1947, Serial No. 737,366. Divided and this application December 1, 1949, Serial No. 132,838

4 Claims. (Cl. 242—72)

1

The invention relates to reels for strip material in coil form and has more particular reference to a reel of the centering type having a plurality of reel supporting arms movable radially outward or inward to grip or release a coil supported thereby.

An object of the invention is to provide a spindle reel of the centering type having horizontally disposed arms mounted for movement in a radial direction with respect to a rotatable spindle whereby a coil of metal stock may be securely gripped by expanding movement of the arms and may be released when the arms are moved in a contracting direction.

Another object of the invention resides in the provision of a spindle reel having horizontal coil supporting arms and which may be hydraulically actuated by longitudinal movement of a central member extending through the spindle shaft of the reel.

Another object of the invention resides in the provision of an improved spindle reel as described wherein the horizontal coil supporting arms are actuated into an expanding or contracting direction by the longitudinal movement of a sleeve having telescoping relation with the spindle shaft of the reel.

A more specific object of the invention resides in the provision of cam members on the arms and sleeve respectively having interlocking relation and which effect radial movement of the arms as a result of longitudinal movement of the sleeve.

With these and various other objects in view, the invention may consist of certain novel features of construction and operation as will be more fully described and particularly pointed out in the specification, drawings and claims appended hereto.

In the drawings, which illustrate an embodiment of the invention, and wherein like reference characters are used to designate like parts—

Figure 1 is a perspective view of the hydraulically actuated centering reel for coil stock material comprising the present invention; and

Figure 2 is a longitudinal sectional view of the reel of Figure 1 illustrating in detail the several improved features of the same.

Referring to the drawings, the spindle reel selected for illustrating the present invention essentially consists of a base 10 having end members 11 and 12 and side members 13 and 14 providing supporting means for the spindle shaft 15. The side members 13 and 14 slope diagonally, being directed toward each other, and at their

2

apex said members together with 11 and 12 support the housing 16 of cylindrical form and which is disposed horizontally. At its respective ends the housing is provided with the roller bearings 17 for journaling the spindle shaft 15, which shaft projects from the respective ends of said housing. The forward projecting end of the spindle shaft has the various elements for supporting the coil associated therewith, whereas, 10 the rear projecting end of the shaft is associated with hydraulic driving means for operating the reel.

The spindle shaft is mounted within housing 16 by being inserted from the forward end of the supporting structure or standard since it will be observed that this end of the housing is closed by the face plate 18 which is secured in place by screws 20. The forward projecting end of the spindle shaft carries the circular plate 21 which 20 is suitably secured to the shaft immediately adjacent face plate 18. Said plate, which is of fairly large diameter, is flanged as at 22 and has a plurality of slots 23 extending radially of the plate and spaced around the central hub of the same. The slots 23 receive the rear portion 24 of the coil supporting arms, indicated in their entirety by 25, and said slots confine the arms for movement in a radial direction. This radial movement of the arms when in an outward direction expands the arms for the purpose of gripping the central opening of a coil of metal stock or the like whereby the coil is securely held and thus supported by the arms. When the radial movement is in an inward direction the coil is released and the same may be removed, or, if the reel is empty, a coil may be located thereon. The rollers 26, journaled at the rear of portion 24, have rolling contact with the flange part of hub member 27 to which the plate 21 is secured and by means of which the plate is fixed to the spindle shaft 15 so as to rotate therewith. The said flange part of hub member 27 is provided with a plurality of radially extending slots which coincide with 23 so that the rear portion 24 of 30 the respective arms extends through the aligned openings thus formed. An additional plate 28 is fixed to circular plate 21 on the front surface thereof adjacent hub 27 and this front plate is likewise apertured to provide a plurality of radial 35 openings. Rollers 30, similar to 26, are also carried by portion 24 of the arms, and these rollers have contact with the face of plate 28. The reel shown in the drawings is provided with four coil supporting arms and each arm is operatively connected with an axially movable

sleeve 32 which structure will now be described.

The sleeve 32 is tubular, having an internal diameter so as to telescope the forward end of the spindle shaft 15, and said sleeve is accordingly mounted for axial movement on the shaft. This movement is permitted by the key 33 which has the additional function of uniting the sleeve in a non-rotatable manner to the shaft. The forward end of sleeve 32 is provided with a cover plate 34 being secured to the sleeve by the screws 35. Adjacent this connection between the cover plate and the sleeve, the sleeve is formed with an annular rim 36 which functions as the front anchoring means for a plurality of longitudinally extending tubes 37. The tubes extend through the fixed slides 38 and 40 and they constitute means for oiling or greasing the diagonal surfaces of the slides since the tubes are in effect capillary members and provision is made for the release of the oil or grease from the tubes at their connection with the slides respectively. The arms 25 are each provided with slides 41 and 42, being fixed thereto in spaced relation, the slides 41 having slidable interlocking relation with their respective slide 38, whereas slides 42 have slidable interlocking relation with their respective slide 40. The slidable interlocking of the slides at their diagonal surfaces functions to retain the arms to the sleeve 32 and to additionally provide for radial movement of the arms upon axial movement of the sleeve.

Movement is imparted to sleeve 32 by the operating rod 43 which extends through the spindle shaft 15 centrally thereof and projects from either end of the shaft. The forward projecting end of rod 43 is fastened by the nut 44 to the cover plate 34 which in effect connects the operating rod with sleeve 32 so that upon longitudinal movement of the rod similar movement is imparted to the sleeve and as a result of the slides and their diagonal interlocking surfaces the arms 25 are caused to move radially of the circular plate 21.

Rod 43 extends rearwardly into the pressure cylinder 45 suitably secured to the rear end of the spindle shaft 15, forming a rear extension of the shaft and which rotates therewith. The piston 46 is fixed to rod 43 and said piston reciprocates within pressure cylinder 45 to effect longitudinal movement of rod 43. The distributor 47 is stationary and does not rotate with cylinder 45 although the same is associated therewith for supplying pressure fluid to the respective ends of the cylinder, the distributor having connection with various supply pipes for the hydraulic fluid as will be more particularly described in connection with the hydraulic mechanism of the invention. When fluid under pressure is supplied by the distributor to the passage 48 the said fluid is admitted to the rear of the cylinder in front of piston 46 and the piston is caused to move forwardly or in a direction toward the right, Figure 2, producing similar movement of rod 43 and sleeve 32 which collapses the arms 25. When the pressure medium from distributor 47 is supplied to passage 49 the same is admitted thereby to the front end of the cylinder, and the piston is caused to move in a direction toward the left. This movement is imparted to rod 43 and thus to the sleeve which has the effect of causing expansion of the arms 25.

The spindle shaft carries a double sprocket wheel 50, the same being suitably secured to the shaft at the connection therewith of the cylinder 45, and the said sprocket is suitably enclosed by

housing 51. An endless chain 52 operatively connects sprocket 50 with the sprockets 53 of smaller size and which are fixed to shaft 54 of the speed reducing mechanism generally indicated by numeral 55. When the spindle is rotated by the paying-off action of the strip material from coil 56, Figure 2, the rotation is transmitted through the endless chain 52 to shaft 54, which thus constitutes the input shaft of the speed reducing mechanism, with the other shaft 57 comprising the output shaft and which is suitably coupled to the fluid pump 58. However, the pump 58 is operated as a fluid motor when it is desired to drive the spindle shaft and rotate the coil supported thereby. In such case shaft 57 constitutes the input shaft and 54 the output shaft. The element 58 is therefore a fluid pressure energy translating device which may operate either as a motor or as a pump of the variable displacement type, being equipped with a compensator for pumping a constant volume although its speed may vary. Said device 58 is manufactured by Vickers Incorporated of Detroit, Michigan under United States Patents Nos. 2,248,076 and 2,277,570.

The spindle reel of the invention provides a plurality of arms disposed in spaced relation with the spindle shaft of the reel and which are supported and operatively connected so as to move radially in an expanding or contracting direction. All the arms move simultaneously and to an equal extent and it will be clearly understood that the arms may be hydraulically actuated by controlling the admission of a fluid under pressure to and from the pressure cylinder 45. The pressure cylinder actuates the rod 43 extending longitudinally and centrally of the spindle shaft and said rod has movement in a longitudinal direction to impart similar movement to the telescoping sleeve 32.

An improved structural feature of the invention resides in the slides fixed to the sleeve and arms respectively and which have interlocking relation on diagonal surfaces. This interlocking of the slides operatively connects the arms and the sleeve and provides for radial movement of the arms upon axial movement of the sleeve.

The structure of the present reel is rugged and durable and the several elements of the combination have been designed for adequately supporting the enormous weight of the large coils adapted to be supported by the reel. Each arm is mounted by the plate member for radial movement and it will be observed that contact with the plate member is maintained by rollers located on the rear of the plate member as well as by rollers located on the front surface of the plate member. This structure in combination with the coating slides renders each arm sufficiently strong and rigid to support its share of the weight of the coil in addition to providing for radial movement of the arms to form a centering reel capable of hydraulic actuation.

This application is a division of our copending application entitled Hydraulic Reel, Serial No. 737,366, filed March 26, 1947.

The invention is not to be limited to or by details of construction of the particular embodiment thereof illustrated by the drawings as various other forms of the device will of course be apparent to those skilled in the art without departing from the spirit of the invention or the scope of the claims.

What is claimed is:

1. In a reel of the type described, in combina-

tion, a spindle shaft journalled by supporting means on a substantially horizontal axis and positioned to provide a projecting reel portion, a plate member fixed to the projecting portion of the spindle shaft and having a plurality of radial slots formed therein, a plurality of coil supporting arms disposed parallel to the spindle shaft and extending through the slots respectively whereby the arms are mounted by the plate member for radial movement, a sleeve member telescoping the projecting portion of the spindle shaft and mounted thereby for axial movement, coacting slides fixed to the sleeve member and to the arms respectively and each pair having inter-engaging diagonal surfaces whereby axial movement of the sleeve member will produce radial movement of the arms, and an operating rod extending through the spindle shaft and connecting with the sleeve member for moving the member in an axial direction.

2. In a reel of the type described, in combination, a spindle shaft journalled by supporting means on a substantially horizontal axis and positioned to provide a projecting reel portion, a plate member fixed to the projecting portion of the spindle shaft and having a plurality of radial slots formed therein, a plurality of coil supporting arms disposed parallel to the spindle shaft and extending through the slots respectively whereby the arms are mounted by the plate member for radial movement, a sleeve member telescoping the projecting portion of the spindle shaft and mounted thereby for axial movement, coacting slides fixed to the sleeve member and to the arms respectively and each pair having inter-engaging diagonal surfaces whereby axial movement of the sleeve member will produce radial movement of the arms, an operating rod extending through the spindle shaft and connecting with the sleeve member for moving the member in an axial direction, and a pressure cylinder at the end of the spindle shaft opposite the forwardly projecting portion for operating the operating rod.

3. In a reel of the type described, in combination, supporting means, a spindle shaft journalled by the supporting means on a substantially horizontal axis and positioned to provide a vertically projecting portion, a plate member fixed to the projecting portion of the shaft at the inner end thereof adjacent the supporting means, a plurality of coil supporting arms disposed in spaced relation circumferentially around the projecting portion of the shaft and extending parallel thereto for approximately the length of said projecting portion, means mounting the arms at one end thereof on the plate

member for movement in a radial direction only and which prevents longitudinal movement of the arms in an axial direction, a sleeve member telescoping the projecting portion of the spindle shaft and being mounted thereby for axial movement, means fixed to the sleeve and to each coil supporting arm and having slidale interengaging relation for connecting the sleeve member with each coil supporting arm whereby axial movement of the sleeve member will produce radial movement of the arms, and an operating rod extending through the spindle shaft and connecting with the sleeve member for moving the member in an axial direction.

4. In a reel of the type described, in combination, supporting means, a spindle shaft journalled by the supporting means on a substantially horizontal axis and positioned to provide a forwardly projecting portion, a plate member fixed to the projecting portion of the spindle shaft at the inner end thereof adjacent the supporting means, a plurality of coil supporting arms disposed in spaced relation circumferentially around the forwardly projecting portion of the spindle shaft and extending parallel for approximately the length of said projecting portion, roller means mounting the arms at one end thereof on the plate member for movement in a radial direction only and which prevents longitudinal movement of the arms in an axial direction, a sleeve member telescoping the projecting portion of the spindle shaft and being mounted thereby for axial movement, slide members fixed to the sleeve and to each coil supporting arm to form pairs having slidale interengaging relation for connecting the sleeve member with each coil supporting arm whereby axial movement of the sleeve member will produce radial movement of the arms, an operating rod extending through the spindle shaft and connecting with the sleeve member for moving the member in an axial direction, and a pressure cylinder at the end of the spindle shaft opposite the forwardly projecting portion for actuating the operating rod.
